UNITED STATES PATENT OFFICE

VINCENT VANSHURA, OF NEW YORK, N. Y.

DESIGN FOR A COMBINATION ASH TRAY AND STAND FOR SMOKERS' ARTICLES

Application filed November 28, 1931. Serial No. 41,905. Term of patent 7 years.

To all whom it may concern:

Be it known that I, VINCENT VANSHURA, a citizen of the United States, and a resident of New York, in the county of Bronx and State of New York, have invented a new, original, and ornamental Design for a Combination Ash Tray and Stand for Smokers' Articles, of which the following is a specification, reference being had to the accompanying drawings, forming part thereof.

bination ash tray and stand for smokers' articles, showing my new design,

Figure 2 is a side elevational view thereof, and

I claim:

The ornamental design for a combination ash tray and stand for smokers' articles, as shown.

VINCENT VANSHURA.
